UNITED STATES PATENT OFFICE

119,260

DESIGN FOR A GAME BOARD

Jacob E. Gould, Detroit, Mich.

Application December 11, 1939, Serial No. 88,823

Term of patent 7 years

To all whom it may concern:

Be it known that I, Jacob E. Gould, a citizen of the United States, residing at Detroit, Wayne County, Michigan, have invented a new, original, and ornamental Design for a Game Board, of which the following is a specification, reference being had to the accompanying drawing, forming a part thereof, in which

Fig. 1 is a top plan view of the game board showing my design;

Fig. 2 is a side elevational view thereof;
Fig. 3 is a sectional view thereof taken substantially on the line 3—3 of Fig. 1 in the direction of the arrows.

I claim:

The ornamental design for a game board, as shown.

JACOB E. GOULD.
